UNITED STATES PATENT OFFICE.

ERASTUS E. WINKLEY AND FRED V. HART, OF LYNN, MASSACHUSETTS, ASSIGNEES
TO UNITED SHOE MACHINERY CORPORATION, OF PATERSON, NEW JERSEY, A COR-
PORATION OF NEW JERSEY.

SHOE-PRESSING MACHINE.

Application filed July 8, 1925, Serial No. 42,213. Renewed December 19, 1927.

This invention relates to shoe pressing machines and is illustrated as embodied in a leveling machine of the so-called automatic roll type.

5 In the use of this type of machine as commonly constructed, the shoe is held on a jack and oscillated back and forth under a heavily spring-pressed leveling roll located at the end of a horizontally pivoted arm which permits the roll to yield vertically under the 10 spring pressure in accordance with the irregularities in contour of the shoe sole.

It was found that in leveling shoes having high arched shanks the roll might drop from 15 the forepart to the shank with a considerable blow instead of rolling down into the shank with a substantially uniform pressure, and that in the reverse movement the roll tended to drag the damp sole toward the ball line, 20 sometimes resulting in undesirable distortion. To meet this difficulty, there was provided a cam which controlled the spring pressure, having depressions into one or another of which the cam follower fell as the 25 roll passed at different times over the ball line of the shoe, thereby relieving a substantial part or all of the spring pressure as the roll passed over this part of the shoe.

However, in the case of men's shoes, for example, which have much more nearly flat bottoms, such variation of the roll pressure was found to be unnecessary. With this in view, and to provide a leveling machine of the roll pressure type which would be better adapted 35 for treating both of the types of shoes referred to, the invention of E. E. Winkley and H. A. Davenport, described and claimed in Letters Patent No. 1,667,761, granted on May 1, 1928, provided for the use of removable plugs for the depressions in the cam above mentioned, which raised the operative surface of the cam at such places to the level of the neighboring portions of the cam.

40 It is a principal object of the present invention still further to improve shoe-pressing or leveling machines in this respect and to provide simple and conveniently operable means for changing a pressure cycle adapted for one shoe to a cycle adapted for a shoe of different characteristics. To this end the illustrative machine is provided with two alternative pressure mechanisms permanently in the machine, such that one can be substituted for the other at will. Thus any diffi-

culty due to loss of non-permanent parts of 55 the machine is avoided, and much time can be saved in changing the machine over from one condition to the other. One of these mechanisms relieves the pressure at the desired points and the other diminishes the relief or 60 entirely prevents relief at some or all of such points. In the embodiment shown, there is provided a primary cam and a cooperating pressure member operating to transmit pressure to the shoe relieved by suitable depressions in the cam, and a secondary cam and pressure member operating when desired to inhibit pressure relieving movements of the primary pressure member, which is thus prevented from falling into the relief depressions in the primary cam. 70

In one aspect, therefore, the invention consists in a leveling machine having a pressure mechanism with a pressure cycle of certain characteristics and a mechanism for varying 75 this cycle better to adapt it to the needs of shoes to which these characteristics are not fully adapted.

In another aspect the invention comprises primary and secondary pressure mechanisms, 80 the latter of which inhibits certain operative characteristics of the former.

In another aspect the invention comprises a pressure member arranged to be governed by either of a plurality of pressure controlling 85 cams at will.

If another aspect the invention provides means operating automatically to decrease the pressure between the shoe and the leveling tool at predetermined points in the operation 90 of the tool and means adjustable by the operator to modify the operation of the last-named means.

These and other features of the invention comprising certain novel combinations and 95 arrangements of parts will be understood from the following description of a preferred embodiment thereof selected for purposes of illustration and shown in the accompanying drawings in which,

Fig. 1 shows a fragmentary side elevation of a machine of the type illustrated in the Letters Patent hereinbefore mentioned with the present invention embodied therein, and

Fig. 2 is a perspective of a part thereof. 105

In the disclosed machine, the shoe 10 is held in a jack comprising a heel post 12 and a toe post 14 mounted to oscillate upon a rock

shaft 16 in a predetermined cycle to carry the shoe back and forth under the leveling tool or roll 18. The leveling roll is mounted upon the end of an arm 20 pivoted at 22 on the main frame for movement in a vertical plane. A heavy spring 24 rests at its lower end upon a link 26 pivoted at 28 on the frame and having a vertical link 30 pivoted to it at its front end. The upper end of the link 30 is pivoted to the arm 20. The upper end of the spring 24 supports a plunger 32 which is arranged to be forced downwardly by a lever 34 pivoted at 36 on the main frame and connected by a link 38 to a lever 40 pivoted at 42 on the main frame. The lever 40 carries a cam roll 44 at its end substantially under the link 38 which contacts with a cam 46 which is rotated on a shaft 48 once in each operation cycle. The low places or notches on the cam 46 permit the link 38 to drop, releasing the spring 24 and thus diminishing or relieving the pressure on the shoe. The high points of the cam raise the link 38 and force down the spring, thus forcing the roll 18 firmly against the shoe. In other words, the low places correspond to pressure minima, and the high places to pressure maxima.

Fig. 1 shows the machine at the beginning of a leveling operation with the cam roll 44 in the notch 50. The cam as shown in Fig. 1 rotates counter clockwise. The high portion 52 provides for the traverse of the roll from the toe down the forepart to the ball line. The low portion 54 releases the pressure at the ball line. The high portion 56 provides for traverse of the roll down the outside of the shank and back again to the ball. The low portion 58 provides for a release of pressure at the ball line. The high portion 60 provides for travel of the roll along the outside of the forepart to the toe and down the inside of the forepart to the ball. The low portion 62 provides for a release of pressure at the ball line again. The high portion 64 provides for a traverse of the roll along the inside of the shank to the breast and back again to the ball. The low portion 66 provides for a release of pressure at the ball and the high portion 68 for a traverse from the ball down the forepart to the end of the operation at the toe. The high portion 68 is shorter than the high portion 52 because the inside of the forepart is considerably shorter than the outside, due to the diagonal position of the ball line.

It will be understood, of course, that the jack 12, 14 is operated by the power mechanism so as to produce movements of the shoe under the roll corresponding to the preceding description. A more detailed description of the mechanism and of the operation thus far described will be found in the Letters Patent hereinbefore mentioned.

The above described cycle of operation is that used upon high arched shoes, in particular, women's shoes. In leveling such shoes,

release of leveling pressure at the ball line is advisable to insure against breakage of the last as the roll passes over the ball line toward the breast, at which time it tends to fall down the steep shank with a severe blow; and conversely, to insure against damage to the shoe due to dragging on the dampened sole as the roll is crowded up over the ball line under pressure.

In the case of shoes having flatter bottoms, as in men's shoes, it is unnecessary and in many cases prejudicial to the best leveling to relieve the pressure as described above. Accordingly, to avoid undesired pressure relief, there is mounted integrally with the cam 46 on the same shaft 48 a smaller cam 70 having, as shown, only one low portion 72, the remainder of its periphery being circular. This cam turns with the cam 46 and cooperates with a roll 74 on the end of an arm 76 pivoted at 78 to the lever 40. A manually operated gravity latch 80 is pivoted to the lever 40. When this latch is in the position shown in Fig. 1, it is out of contact with the arm 76 and free relative pivotal movement between the arm 76 and the lever 40 is permitted. When, however, the latch is thrown over to the position shown in Fig. 2, it contacts with the arm 76 as shown in Fig. 2 and thus limits upward movement of the arm 76 relatively to the lever 40. There being no low places in the cam 70 corresponding to the low places of the cam 46 except the depression 72 corresponding to the depression 50, the arm 76, when the latch is in the Fig. 2 position, will hold up the lever 40 and prevent the roll 44 from falling into the other low portions of the cam 46 as they come around, thus maintaining pressure on the shoe during the whole operation, while when in the Fig. 1 position it is ineffective in this respect. The head 82 of the latch 80 is heavy and holds the latch in either of its two positions as placed by the operator. The lever 40 and the arm 76 may be regarded as constituting together a compound lever arm.

Thus the machine can be used interchangeably to level shoes having high arched shanks in the case of which certain pressure relief is desired and also to level flat bottomed shoes in which such pressure relief is unnecessary or undesirable, without any loss of time on the part of the operator in inserting parts into the machine or in hunting for them if mislaid.

It is, of course, not necessary that the cam 70 be constructed to inhibit the action of all the low places of the cam 46. It can be constructed to render ineffective any selected depressions as required in the cam 46. It will thus be seen that we have provided a simple, compact and conveniently operable mechanism for changing a pressure cycle adapted to one shoe to a cycle required by a shoe of different characteristics. The illustrated ma-

chine comprises two alternative pressure mechanisms, a primary and a secondary mechanism, both mounted as permanent portions of the machine and comprising respectively 5 the cams 46 and 70, the latter of which inhibits certain characteristics of the former. From another point of view it may be said that the lever 40 and its pressure applying connections are arranged to be governed by 10 either of the cams 46 and 70 at will. These cams obviously effect pressure cycles of essentially different characteristics, by the term "cycle" being meant herein the history or time-graph of the pressure during a leveling 15 operation on a particular shoe.

Having described our invention, what we claim as new and desire to secure by Letters Patent of the United States is:—

1. In a machine of the class described, 20 means for holding a shoe and a tool relatively movable to cause the tool to treat successive portions of a shoe progressively, a pressure mechanism for effecting a predetermined cycle of variable pressure between the shoe 25 and the tool as they move relatively, and means operatively connected with said pressure mechanism and adjustable at the will of the operator to vary the quantitative relations 30 between different parts of the pressure cycle according to the requirements of a given shoe.

2. In a shoe leveling machine, means for holding a shoe and a leveling tool relatively movable to cause the tool to treat successive 35 portions of a shoe progressively, a pressure mechanism for effecting a predetermined cycle of variable pressure between the shoe and the tool as they move relatively, and means operatively connected with said pressure mechanism and adjustable at the will of the operator to vary certain portions only of 40 the pressure cycle according to the requirements of a given shoe.

3. In a shoe pressing machine, means for holding a shoe, a tool arranged to press the shoe, and a plurality of alternative pressure mechanisms permanently mounted in the machine for creating pressure between the tool and shoe, arranged for the substitution of one for the other at the will of the operator. 50

4. In a shoe pressing machine, means for holding a shoe, a tool arranged to operate progressively over the shoe to press it, a pressure mechanism having a pressure cycle of certain characteristics, and a mechanism for inhibiting certain of these characteristics as regards selected shoes. 55

5. In a shoe pressing machine, means for holding a shoe, a tool arranged to operate progressively over the shoe to press it, a pressure mechanism having a pressure cycle of certain characteristics, and a mechanism for modifying certain only of these characteristics as regards selected shoes. 60

6. In a shoe pressing machine, means for

holding a shoe, a tool arranged to operate progressively over the shoe to press it, a pressure mechanism for diminishing the pressure at predetermined points of the pressure cycle, and a mechanism for modifying the diminution of pressure at certain of such points, 70 while leaving unaltered those portions of the cycle other than such points.

7. In a shoe pressing machine, means for holding a shoe, a tool arranged to operate 75 progressively over the shoe to press it, a pressure mechanism for substantially relieving the pressure at predetermined points of the pressure cycle, and a mechanism for inhibiting the relief of pressure at certain of such 80 points.

8. In a machine of the class described, means for holding a shoe and a tool relatively 85 movable to cause the tool to treat successive portions of a shoe progressively, a pressure mechanism comprising a cam for diminishing 90 the pressure between the shoe and the tool at predetermined points of the pressure cycle, and a second cam for inhibiting the action of the first-named cam at certain of such points. 95

9. In a shoe leveling machine, means for holding a shoe, a tool arranged to operate progressively over the shoe under pressure, a cam for effecting a predetermined cycle of pressure between the shoe and the tool during 100 a pressing operation, a second cam for effecting a different predetermined cycle of pressure between the shoe and tool during a pressing operation, and means for placing either cam at will in operation on a particular shoe. 105

10. In a shoe leveling machine, means for holding a shoe, a tool arranged to operate progressively over the shoe under pressure, a cam for effecting a predetermined cycle of pressure between the shoe and the tool during 110 a pressing operation, a second cam for effecting a different predetermined cycle of pressure between the shoe and tool during a pressing operation, and a mechanism arranged to cooperate with either cam at will to cause that cam to control the pressure cycle on a particular shoe.

11. In a shoe leveling machine, means for holding a shoe, a tool arranged to operate progressively over the shoe under pressure, a cam for effecting a predetermined cycle of pressure between the shoe and the tool during 115 a pressing operation, a second cam for effecting a different predetermined cycle of pressure between the shoe and tool during a pressing operation, and a lever mechanism arranged to cooperate with either cam at will to cause that cam to control the pressure cycle 120 on a particular shoe.

12. In a shoe pressing machine, means for holding a shoe, a tool arranged to operate progressively over the shoe under pressure, a cam for effecting a predetermined cycle of pressure between the shoe and the tool during 125 a pressing operation, a second cam for 130

effecting a predetermined pressure cycle which lacks certain of the pressure-minima of the first-named cycle, and means for utilizing either cam at will in operation upon a particular shoe.

13. In a machine of the class described, means for holding a shoe and a tool constructed and arranged for relative movement to cause the tool to treat successive portions of the shoe progressively under pressure, means operating automatically to decrease the pressure at predetermined points in the operation of the tool, and means adjustable at the will of the operator to modify the operation of said last-named means at a plurality of such points without disturbing the remainder of the cycle.

14. In a machine of the class described, means for holding a shoe and a tool constructed and arranged for relative movement to cause the tool to treat successive portions of the shoe progressively under pressure, means operating automatically to relieve the pressure at predetermined points in the operation of the tool, and means adjustable at the will of the operator to prevent the operation of said last-named means.

15. In a shoe pressing machine, means for holding a shoe, a tool arranged to operate progressively over the shoe under pressure, a lever for imparting pressure to the tool and shoe, a cam for controlling the lever in accordance with a predetermined pressure cycle, a second cam for controlling the lever in accordance with a different predetermined pressure cycle, and means for causing either cam at will to control the lever.

16. In a machine of the class described, means for holding a shoe and a tool relatively movable to cause the tool to treat successive portions of a shoe progressively, a pressure mechanism for effecting a predetermined cycle of variable pressure between the shoe and the tool as they move relatively, comprising a cam, the cam having depressions into which the lever falls to effect pressure-minima, and a mechanism operative at will to prevent the falling of the lever into certain of the depressions in operating on a particular shoe.

17. In a shoe pressing machine, means for holding a shoe, a tool arranged to operate progressively over the shoe under pressure, a lever for imparting pressure to the tool and shoe, a cam for controlling the lever in accordance with a predetermined pressure cycle, the cam having depressions into which the lever falls to effect pressure-minima, and a second cam operative at will to prevent the falling of the lever into certain of the depressions in operating on a particular shoe.

18. In a shoe pressing machine, means for holding a shoe, a tool arranged to operate progressively over the shoe under pressure, a lever for creating pressure between the tool

and shoe having a compound arm, and two cams, one cooperating with each branch of the compound lever arm, to produce differing cycles of pressure between the shoe and the tool at will.

19. In a shoe pressing machine, means for holding a shoe, a tool arranged to operate progressively over the shoe under pressure, a lever for causing pressure between the tool and shoe, a cam cooperating with the lever to produce a predetermined cycle of pressure between the tool and shoe, an arm movably mounted on the lever, a second cam arranged to cooperate with the arm to produce a different cycle of pressure between the tool and shoe, and means for operatively locking the arm to the lever to render the second cam effective.

20. In a shoe pressing machine, means for holding a shoe, a tool arranged to operate progressively over the shoe under pressure, a lever for causing pressure between the tool and shoe, a cam cooperating with the lever to produce a predetermined cycle of pressure between the tool and shoe, an arm movably mounted on the lever, a second cam arranged to cooperate with the arm to produce a different cycle of pressure between the tool and shoe, and a stop on the lever operable to limit the movements of the arm relatively to the lever to render the second cam effective.

21. In a shoe pressing machine, means for holding a shoe, a tool arranged to operate progressively over the shoe under pressure, a lever for causing pressure between the tool and the shoe, a cam cooperating with the lever to produce a predetermined pressure cycle, an arm pivoted to the lever, a second cam cooperating with said arm, and a stop which can be positioned to prevent relative movement of the lever and the arm under the thrust of the second cam, the second cam being shaped to lift the lever away from certain low portions of the first-named cam when the stop is so positioned.

22. In a machine of the class described, means for holding a shoe and a tool arranged for relative movement to cause the tool to treat successive portions of the shoe progressively, a pressure mechanism for effecting pressure between the tool and the shoe in a predetermined pressure cycle, means for altering said pressure cycle, and a member operative at will to cause said last-named means to become effective for any selected cycle of operations of the machine.

23. In a machine of the class described, means for holding a shoe and a tool arranged for relative movement to cause the tool to treat successive portions of the shoe progressively, and a pressure mechanism having alternatively operable members for effecting pressure between the tool and the shoe in a selected one of a plurality of pressure cycles of essentially differing characteristics at will,

24. In a machine of the class described, means for holding a shoe, a tool arranged to operate progressively along the shoe, a pressure mechanism for effecting pressure between the tool and the shoe in a predetermined pressure cycle, and mechanism permanently mounted in the machine for altering a selected portion of the said cycle for operating on a particular shoe.
- 10 25. In a shoe pressing machine, means for holding a shoe, a tool arranged to operate progressively along the shoe, a pressure mechanism for effecting pressure between the tool and the shoe in a predetermined pressure cycle, and a mechanism comprising a member having an operative and an inoperative position in the former of which it is arranged to alter a selected portion of the said cycle for operating on a particular shoe.
- 15 26. In a shoe leveling machine, means for holding a shoe, a tool arranged to operate progressively along the shoe, a pressure mechanism for effecting pressure between the tool and the shoe in a predetermined cycle, and a
- mechanism comprising a pivoted member having an operative and an inoperative position in the former of which it is arranged to alter the said cycle for operating on a particular shoe.
- 20 27. In a shoe leveling machine, means for holding a shoe, a tool arranged to operate progressively over the shoe under pressure, a lever for causing pressure between the tool and shoe, a cam cooperating with the lever to produce a predetermined cycle of pressure between the tool and shoe, an arm movably mounted on the lever, a second cam arranged to cooperate with the arm to produce a different cycle of pressure between the tool and shoe, and a member pivoted on the lever and operable to limit the movements of the arm relatively to the lever to render the second cam effective.

In testimony whereof we have signed our names to this specification.

ERASTUS E. WINKLEY.
